US00D672663S

(12) **United States Design Patent**
Baker et al.

(10) **Patent No.:** US D672,663 S
(45) **Date of Patent:** ** Dec. 18, 2012

(54) **CONTAINER**

(75) Inventors: **Gerald Baker**, Wauwatosa, WI (US);
Rowdy Holstine, Hartford, WI (US);
Elizabeth Metzger, Waukesha, WI (US);
Jianwen Hu, Neshotah, WI (US)

(73) Assignee: **Silgan Containers LLC**, Woodland Hills, CA (US)

(**) Term: **14 Years**

(21) Appl. No.: **29/385,514**

(22) Filed: **Feb. 15, 2011**

OTHER PUBLICATIONS

U.S. Appl. No. 29/318,036, filed May 12, 2008, Murphy et al.

(Continued)

Primary Examiner — Keli L Hill

(74) *Attorney, Agent, or Firm* — Reinhart Boerner Van Deuren s.c.

CLAIM

The ornamental design for a container, as shown and described.

DESCRIPTION

FIG. 1 is a perspective view of the claimed design; FIG. 2 is a front view of the claimed design of FIG. 1, the rear view, the left side view and the right side view being the same as the front view;

FIG. 3 is a top view of the claimed design of FIG. 1; and, FIG. 4 is a bottom view of the claimed design of FIG. 1.

The broken lines shown are included for the purpose of illustrating the unclaimed portions of the article and form no part of the claim.

1 Claim, 3 Drawing Sheets
